(57) **CLAIM**

The ornamental design for a pipe sealing tool, as shown and described.

DESCRIPTION

FIG. 1 is a side elevational view of a pipe sealing tool showing my new design, the opposite side elevational view being a mirror image;

FIG. 2 is a top plan view thereof;

FIG. 3 is a bottom plan view thereof;

FIG. 4 is a front elevational view thereof; and,

FIG. 5 is a rear elevational view thereof.

The pipe sealing tool is shown broken away in the views to indicate indeterminate length.
